END CONSTRUCTION FOR MINE CARS

Warren V. Johnson and Robert C. Kepner,
Bloomsburg, Pa., assignors to American Car
and Foundry Company, New York, N. Y., a
corporation of New Jersey

Application September 12, 1935, Serial No. 40,223

14 Claims. (Cl. 105—364)

The present invention deals with improvements in mine and other rail cars and especially with end constructions for the low-floor type of mine car.

Previous mine cars have been built in which the end was formed of a rolled section to which was attached members to form a bumper support, other members to form a portion for attachment of the floor and reenforcing members for attachment of the draw member. These constructions were generally wasteful of material and relatively weak considering the amount of metal that was used in their fabrication. It is an object, therefore, of the present invention to form a structure in which the metal is distributed to greater advantage than heretofore.

Another object of the invention is the elimination of the end sill as an element.

A further object of the invention is the provision of an end construction which forms part of the car floor.

A still further object of the invention is the provision of an end construction capable of carrying the bumper and draft means and which of itself is strong enough to resist the shocks of service.

These and other objects will be apparent to one skilled in the art after a study of the following description, together with the accompanying drawings, in which:

Figure 1 is a sectional view of the improved end construction;

Fig. 2 is a plan view of the end construction of Fig. 1, parts thereof being broken away to show the method of attachment of certain parts;

Fig. 3 is a front elevational view of the construction shown in Fig. 1, certain portions being broken away to more clearly show the attachment and relation of certain parts;

Figs. 4, 5 and 6 are views similar respectively to Figs. 1, 2 and 3, but, showing a modification thereof;

Fig. 7 is a sectional view of a still further modification with portions of the bumper block broken away to more clearly show the side sill connections;

Fig. 8 is a plan view of the construction of Fig. 7, and

Fig. 9 is a front elevational view of the end construction of Fig. 7.

Referring now to the drawings in detail and first to the modification shown in Figs. 1 to 3; it is seen that the end construction is secured to the side sills S and has a portion provided for the support and attachment of the floor F.

The end member is formed principally of a formed upper plate 2 and a lower, preferably flat, plate 4. The lower plate extends from side sill to side sill and has its end portions resting upon and rigidly secured to the inturned flanges 6 of the side sills, thus forming a rigid connection between the sills which will prevent any weaving of the sills relative to each other. The upper plate is formed with a horizontal portion 8 adapted to be secured to the lower plate by means 10 at 10 points spaced from the edge of the lower plate, thus providing a ledge 12 upon and to which the floor is supported and secured. The plate is inclined upwardly from the lower horizontal portion to form a part 14 and is then directed outwardly in a horizontal plane to form a portion 16 spaced above the lower plate. In order to brace the inclined floor portion a short backing angle is arranged in the angle defined by the bottom plate 4 and the inclined portion 14 of plate 2, said bracing angle extending transversely of the car and having a leg 18 riveted or otherwise secured to the bottom plate and a vertical leg 20 abutting, at its upper edge portion, the sloped portion 14 to which it may be welded if desired. 15

Vertically arranged plates or bracing members 22 are provided to prevent spreading of the top and bottom plates and each is formed with a top edge 24 conforming to the contour of the top plate to which it is welded as at W. The rear end portion of each bracing plate abuts the vertical leg 20 of the backing angle, while the lower edge is provided with a tongue or projection 26 adapted to extend through slots in the lower plate in order to be readily welded thereto as at U. The front lower edge of each plate is also welded to the lower plate as is clearly shown at W. 30

The top plate 2 is supported at its end portions by angles having one leg 28 underlapping and secured to the plate, while the other leg 30 is secured to the side sill web, thus giving an additional side sill connection. The side sills, bracing plates, top and bottom plates, and backing angle form three pockets into which suitably shaped wood members 32 may be inserted and secured in 40 place by through bolts 34. The wood blocks extend beyond the top and bottom plates to contact the web of a channel-shaped bumper element B, the flanges of which overlap and are loosely connected to the top and bottom plates 2 and 4 by 45 the through bolts; the top and bottom plates 2 and 4 constituting bearing surfaces for the flanges of the bumper element B as will be apparent. Coupler tongue C is formed of a flat bar suitably bent as shown to conform in general to 50

the contour of the top plate to which it is secured. The coupler tongue is also formed with a horizontal portion 36, having an opening to receive the coupler pin P and this portion is joined to the 5 remainder of the strap by an inclined portion 38 suitably supported by filler 40 welded to the tongue and top plate. The usual belt or binder 42 may be provided and is shown as carried by through bolts 44 although this belt may be connected to the bottom plate as is shown in Figs. 4 to 10 6 and now to be described.

The modification shown in Figs. 4 to 6 inclusive is in many respects similar to the form just described in connection with Figs. 1 to 3 inclusive and the same reference numerals have therefore been used wherever possible to indicate like parts. In this modification the top plate has been changed in order to eliminate the backing angle as a separate element by extending the horizontal portion 8 and connecting this to the sloping part 14 by a vertical portion 21 which corresponds in function with the vertical portions of the brace members shown in Figs. 1 to 3 inclusive and Figs. 7 to 9 inclusive; the construction of 15 Figs. 7 to 9 inclusive being hereinafter particularly described. As will be obvious, in the construction of Figs. 4 to 6 inclusive, the brace 21 is interposed between the lower plate 4 and the inclined portion 14 of the upper plate 2. The 20 pressing of the top plate in the form shown forms, of course, a pocket but, in practice, this fills up with fine coal which becomes packed and forms a continuation of the slope. The belt or binder 42 is connected to the bottom plate by 25 means of short rivets or other means 45.

The modification shown in Figs. 7 to 9 inclusive is a much simpler and more economical constructional than those previously described in that the number of parts has been materially reduced. The bottom plate 52 extends in a single 30 plane from a point adjacent the end of floor plate F to or slightly beyond the ends of the side sills to form a lower support for the bumper block 54. The belt or binder 56 is attached to the bottom plate and to the side sills by rivets 57, thus aiding in the support of the bottom plate whose edge portions are securely fastened to the side sill flanges 58 as clearly shown.

The top plate is formed of a single piece of 35 metal pressed or otherwise formed to the desired shape and is provided with a rear horizontal portion 60 through which securing means 62 pass in order to tie the bottom plate, top plate and floor plate together. Incline 64 extends upwardly from the rear portion of the plate and then horizontally outward as at 66 over a majority of its area to provide an upper protecting portion for the bumper block. Pressed in the upper horizontal portion is a coupler pocket 55 formed with inclined back wall 68, side walls 70 and top wall 72 which is parallel to the portion 66. The top wall has welded thereto a flat plate 74 in order to provide sufficient bearing metal for the coupler pin P. The side walls are cut back 60 as at 76 in order to permit application and movement of the bumper cap B, which is of usual design. A short pressed channel having a horizontal flange 78, web 80 and inclined flange 82 securely ties the top and bottom plates together 65 and forms a backing for the wood bumper block previously mentioned. It is necessary that this channel be short enough to allow insertion of a 70 backing tool between its end and the side sill in order that the rivets connecting the end construction to the side sill may be driven. The 75

edges of the top plate are bent downwardly as at 84 to receive securing means 86 which fasten the plate to the side sill. It is seen that with this construction an end member is fabricated of four pieces which are easily formed, require a minimum of labor and produce a structure of great strength. 5

It is obvious to one skilled in the art that various modifications of the end construction are possible and that such modifications may be 10 made without departing from the scope of the appended claims which, rather than the illustrative description, limit the invention.

What is claimed is:

1. An end construction for low-floor mine or 15 similar cars having side sills and comprising, a substantially horizontal lower plate secured to the side sills and floor, an upper plate secured to said lower plate and side sills, said upper plate being formed with an upwardly inclined portion, transverse bracing means interposed between said bottom plate and inclined portion of the upper plate, and longitudinally arranged bracing means connecting said upper and lower plates and spaced relative to the side sills, said 20 bracing means forming with said plates and side sills pockets for the reception of bumper means.

2. An end construction for low-floor mine or 25 similar cars having side sills and comprising, a substantially horizontal lower plate secured to the side sills and floor, an upper plate secured to said lower plate and side sills, said upper plate being formed with an upwardly inclined portion, 30 bracing means connecting said top and bottom plates to form with said side sills pockets 35 for the reception of bumper means, said bracing means being provided with projecting lugs adapted to be interlocked with one of said plates.

3. An end construction for low-floor mine or 40 similar cars having side sills and comprising, a substantially horizontal lower plate secured to the side sills and floor, an upper plate having a horizontal portion secured to said lower plate and an inclined portion joined to said horizontal portion by a vertically extending portion, and 45 bracing means connecting said upper and lower plates, said bracing means being spaced from the side sills and forming with said top and bottom plates pockets for the reception of bumper means.

4. An end construction for low-floor mine or 50 similar cars having side sills and comprising, a substantially horizontal lower plate secured to the side sills and floor, an upper plate secured to said lower plate and side sills, said upper plate being formed of a single pressing having spaced 55 apart substantially horizontal portions joined together by an inclined portion, at least one of said portions having pressed therein a coupler attachment element and bracing means connecting said top and bottom plates to form a backing 60 means for a bumper block.

5. As an article of manufacture a formed plate for use in car end constructions comprising, spaced apart substantially parallel portions, an inclined portion joining said first named portions and coupler attachment means pressed upwardly from at least one of said portions. 65

6. As an article of manufacture a formed plate for use in car end constructions comprising, 70 spaced apart substantially parallel portions, an inclined portion joining said first named portions and coupler attachment means pressed upwardly from at least one of said portions, said inclined portion and at least one of the parallel 75

- portions having laterally extending attaching portions at each edge.
7. An end construction for low-floor mine or similar cars having side sills and comprising, a substantially horizontal lower plate secured to the side sills and floor, an upper plate secured to said lower plate and side sills, said upper plate being formed with an upwardly inclined portion, bracing means connecting said top and bottom plates to form with said side sills a plurality of longitudinally extending open ended pockets for the reception of bumper means, said bracing means being provided with projecting lugs adapted to be interlocked with one of said plates.
15. 8. An end construction for low-floor mine or similar cars having side sills and comprising, a substantially horizontal lower plate secured to the side sills and floor, an upper plate secured to said lower plate and side sills, said upper plate being formed of a single pressing having spaced apart substantially horizontal portions joined together by an inclined portion, and at least one of said portions having pressed therein a coupler receiving pocket.
23. 9. As an article of manufacture a formed plate for use in car end constructions comprising, spaced apart substantially parallel portions, an inclined portion joining said first named portions and coupler attachment means pressed upwardly from at least one of said portions, said inclined portion having downwardly directed attaching portions at the edges thereof.
30. 10. As an article of manufacture a formed plate for use in car end constructions comprising, spaced apart substantially parallel portions, an inclined portion joining said first named portions and coupler attachment means pressed upwardly from at least one of said portions, at least one of said parallel portions having the opposite edges thereof directed downwardly.
35. 11. An end construction for mine or similar cars having side sills and a floor, comprising a substantially horizontally arranged lower plate secured to the side sills and floor, an upper plate extending between and connected to the side sills, said upper and lower plates extending outwardly of the car beyond the ends of the side sills and said upper plate being formed with a portion inclined upwardly toward the end of the car, a bumper block supported on the lower plate, and bracing means arranged transverse to the longitudinal axis of the car and extending substantially continuously for at least the full width of the bumper block, said bracing means being arranged between the lower plate and said inclined portion of the upper plate and constituting a backing member for said bumper block.
45. 12. An end construction for mine or similar cars having side sills and a floor, comprising a substantially horizontally arranged lower plate secured to the side sills and floor, an upper plate extending between and connected to the side sills, said upper and lower plates extending outwardly beyond the ends of the side sills and said upper plate being formed with a portion inclined upwardly toward the end of the car, a bumper block supported on the lower plate, and bracing means extending transversely of the car with its end portions adjacent the side sills, said bracing means being arranged between the lower plate and the inclined portion of the upper plate and constituting a substantially continuous backing member for the bumper block.
50. 13. An end construction for mine or similar cars having side sills and a floor, comprising a substantially horizontally arranged lower plate secured to the side sills and floor, an upper plate extending between and connected to the side sills, said upper and lower plates extending outwardly beyond the ends of the side sills and said upper plate being formed with a portion inclined upwardly toward the end of the car, a bumper block supported on the lower plate, bracing means extending transversely of the car with its end portions adjacent the side sills, said bracing means being arranged between the lower plate and the inclined portion of the upper plate and constituting a substantially continuous backing member for the bumper block, and a bumper plate having flanges lapping the upper and lower plates.
55. 14. An end construction for mine or similar rail cars having side sills and a floor, comprising a substantially horizontally arranged lower plate secured to the side sills and floor, an upper plate extending between and connected to the side sills, said upper and lower plates extending outwardly beyond the ends of the side sills and said upper plate being formed with a portion inclined upwardly toward the end of the car, a bumper block supported on the lower plate, bracing means extending transversely of the car with its end portions adjacent the side sills, said bracing means being arranged between the lower plate and the inclined portion of the upper plate and constituting a continuous backing member for the bumper block, and a flanged bumper plate having a face portion covering the end of the bumper block, the end portions of the top and bottom plates serving as bearing portions for the flanges of said bumper plate.
